UNITED STATES PATENT OFFICE.

VICTOR H. SLINACK, OF PHILADELPHIA, PENNSYLVANIA, ASSIGNOR TO THE PENNSYLVANIA GLOBE GAS LIGHT COMPANY, OF PHILADELPHIA, PENNSYLVANIA, A CORPORATION OF PENNSYLVANIA.

DESIGN FOR AN INVERTED GAS-BURNER FOR STREET-LIGHTS.

No. 40,057.

Specification for Design.

Patented June 15, 1909.

Application filed April 22, 1909. Serial No. 491,655. Term of patent 14 years.

To all whom it may concern:

Be it known that I, VICTOR H. SLINACK, a citizen of the United States, residing at Philadelphia, in the county of Philadelphia and State of Pennsylvania, have invented a new, original, and ornamental Design for Inverted Gas-Burners for Street-Lights, of which the following is a specification, reference being had to the accompanying drawings, forming part thereof.

The figure is an elevational view of an inverted gas burner for street lights showing my new design.

I claim:

The ornamental design for an inverted gas burner for street lights as shown.

VICTOR H. SLINACK.
